UNITED STATES PATENT OFFICE

2,024,361

TRACK SANDER

Walter H. Hinsch, Chicago, Ill., assignor to Locomotive Firebox Company, Chicago, Ill., a corporation of Delaware

Application July 16, 1934, Serial No. 735,308

6 Claims. (Cl. 291—40)

This invention relates to improvements in track sanders and it consists of the matters hereinafter described and more particularly pointed out in the appended claims.

5 The invention is more particularly adapted to track sanders of the kind shown in the Sellers and Barnett patent, No. 1,949,977 of March 6, 1934 and one of the objects of the present invention is to improve, simplify and reduce the 10 cost of manufacture and installation of such a sander.

15 Another object of the invention is to provide a sander of this kind wherein the sand inlet and duct leading to the sander pipe, as well as the duct and discharge orifice for the motive fluid under pressure is embodied in a single casting, adapted to be welded in place in the sand dome and to have all piping connections outside the dome.

20 Still another object of the invention is to provide a sander of this kind including a sander head which is so formed that when used with others in multiple, they may be arranged and welded together side by side as a unit, thus 25 making it practical to use as many sander heads on each side of the dome as may be required by the number of driving wheels on the locomotive to which the track sander is to be applied.

30 Still a further object of the invention is to provide a sander head capable of being made as a casting and having a longitudinally extending sand duct and a motive fluid duct arranged closely thereto and leading to an orifice that 35 discharges substantially axially into the sand duct, above its sand inlet, the sander head being formed at that end to be disposed without the sand dome with openings for the ready attachment of the sander and air pipes.

40 The above mentioned objects of the invention, as well as others, together with the many advantages thereto will more fully appear as I proceed with my specification.

In the drawing:

45 Fig. 1 is a transverse vertical sectional view through the sand dome or box of a locomotive with my improved structure applied thereto.

Fig. 2 is a horizontal sectional view through the same, as taken on the line 2—2 of Fig. 1, 50 certain of the sander heads being shown in horizontal section.

55 Fig. 3 is a detail vertical sectional view on an enlarged scale as taken on the line 3—3 of Fig. 2.

Fig. 4 is a longitudinal vertical view on an

enlarged scale through one of the sander heads, as taken in the plane of its sand duct.

In general, my improved sander includes a sander head and piping for delivering motive fluid to the head and for delivering sand to the rails. Each sander head is constituted as a casting, preferably of a rectangular cross section and formed with longitudinally extending sand and motive fluid ducts respectively. The sand duct includes a downturned inlet end and the motive fluid duct terminates in a discharge orifice opening substantially axially into the sand duct at its inlet end. Such a casting may be applied to a sand dome, merely by cutting a rectangular opening in the bottom of one side 10 of the dome and then inserting the inlet end of the sander head into the dome through said opening after which the sander head is welded in place to close said opening, air and sand tight. The opposite end of the sander head 15 which is disposed outside of the sand dome is formed to receive the sand and the motive fluid pipes respectively, which may be attached to the head from outside the dome. In a sanding operation, when fluid, such as air under pressure 20 is fed to the sander head, a vacuous condition is established at the inlet end of the sand duct. This draws sand into the sand duct and said sand meets the air blast and mixes therewith, to be discharged out through the sand duct to the 25 sander pipe for delivery to the rails. As there are no bends or traps to be impinged against by the sand blast, as the same is discharged into the sander pipe, the cutting action of the sand 30 is reduced and the period of usefulness of the 35 sander is greatly increased.

Referring now in detail to that embodiment of the invention illustrated in the accompanying drawing:

1 indicates, as a whole, a sand dome or box 40 provided at its bottom end with a flange 2 whereby it may be welded pressure-tight to the shell 3 of a locomotive boiler. As shown herein, the sand dome is circular when viewed in plan and has a central filler opening 4 at the top 45 which may be tightly closed by a cover in the well-known manner.

At each side of the sand dome is one or more sander heads 5, depending upon the size and type of locomotive to which the improved 50 sander is to be applied. As best shown in Figs. 2 and 3, there are two sander heads at each side of the dome.

Each head is preferably in the form of an elongated block of substantially rectangular 55

cross section having flat top, bottom and side surfaces, with rounded corners. In each block is formed a longitudinally extending sand duct 6, the outer end of which is threaded to receive an end of an associated sander pipe 7. The inner end of the block is provided with a downwardly facing inlet nozzle or extension 8 having an inlet mouth 9 which joins the duct 6 by a rounded elbow portion 10. The inlet mouth 9 is preferably made tapering so that its extremity is of a diameter less than that of the duct 6. Also in said sander head and preferably spaced to one side of the sand duct, is a motive fluid or air duct 11 that opens at its outer end 15 through the top of the head. This end of the motive fluid duct is threaded to take an elbow 12 for receiving the associated end of pipe 13 which may lead from a source of air under pressure. Preferably when two of such sander heads are employed at each side of the dome, said elbows face in opposite directions as shown in Fig. 2.

The inner end of the motive fluid duct turns a corner to enter a boss 14 on the inner end of the head, and an orifice 15, connects said inner end of the fluid duct with the inner end of the sand duct. Preferably this orifice which is a drilled hole, is arranged substantially axially of the sand duct. The boss 14 is provided with an end opening 16 whereby the orifice may be drilled from the inner end of the head and this opening is then closed by a screw plug 17.

In installing a pair of such heads in each side of the dome, two of said heads are welded together at the grooves formed by the adjacent top and bottom rounded corners of both heads. These weldings are shown at 19 in Fig. 3. An opening is then cut in the bottom of the dome side of an outline corresponding to the cross section and of a size to receive the two heads welded together as a unit. Such an opening is indicated at 18 in Fig. 1. The inner ends of two of the heads thus welded together as a unit, are inserted through said opening, tangentially to the boiler shell, to such a distance as will bring the inlet mouth of each head a suitable distance above the shell. A line of welding 20 is then run about the opening to secure the heads as a unit in place in the sand dome. Thus the heads are secured together as a unit and are also secured in operative relation, pressure-tight and leak-proof in the dome. If the locomotive requires more sanders, three or four of such heads may be secured together as a unit 55 for attachment to the associated side of the dome. Generally four of such heads as a unit, are the maximum number required.

When fluid such as air, under pressure, enters the duct 11 it discharges through the orifice 15 axially into the inner end of the associated sand duct 6. This discharge of motive fluid creates a vacuous condition in the said end of each sand duct, that siphons or causes a rush of sand through the inlet mouth 9 of the head to mix 65 with said fluid issuing from the orifice. This will cause a movement of the sand through the sand duct into the sander pipe for discharge.

Preferably that end of the sander pipe that is secured in the outer end of the sander head, is straight so as to be disposed axially of the sand duct. Thus there are no bends interposed in the path of the blast to be worn out thereby and there are no pockets or traps in which sand can accumulate. Also there are no such joints 75 as will admit moisture to the sand so that it will

not dampen to there afterwards pack and clog anywhere along its path of discharge to the rails.

It is to be noted that all sander and motive fluid pipe connections are made outside the dome. Therefore when such pipes require removal during servicing of the locomotive, no work need be done within the relatively small confines of the dome.

The sander head comprises a single casting 10 with the plug mentioned and the number of threading or other operations thereon are reduced to a minimum. Thus the head which is of a simple construction may be produced at a low cost.

While in describing the invention, I have referred in detail to the form, arrangement and construction of the various parts thereof, the same is to be considered only in the illustrative sense so that I do not wish to be limited thereto 20 except as may be specifically set forth in the appended claims.

I claim as my invention:

1. In combination with the sand dome of a locomotive, a plurality of sander heads having 25 flat sides engaged and secured together in horizontal alignment to provide a sander head unit, means for securing said unit to said dome near the bottom thereof with the inner end of each head inside and the outer end of each head 30 outside the dome, each head having longitudinally extending sand and motive fluid ducts respectively that open through the outer end of the head and are there formed for the connection of sander and motive fluid pipes respectively, 35 the inner end of each head being formed with a downwardly opening inlet mouth for the sand duct, said inner end being further formed with an orifice which opens from said motive fluid duct substantially axially into the sand duct for 40 the discharge of motive fluid thereto.

2. In combination with the sand dome of a locomotive, having an opening in one side near its bottom, a plurality of sander heads, welded together side by side in horizontal alignment to 45 provide a unit which is engaged and is welded in said opening so that the inner end portion of the unit is disposed inside the dome, and the outer end portion is disposed outside the dome and is there formed for the attachment of sander 50 and motive fluid pipes respectively each sander head having sand and fluid ducts respectively that communicate with each other at the inner end, the inner end of each head being formed to provide a downwardly facing inlet mouth for 55 the associated sand duct.

3. In combination with the sand dome of a locomotive having an opening in one side near its bottom, a plurality of sander heads having flat, engaging side faces, welded together in horizontal 60 alignment to provide a unit which is engaged and welded in said opening so that the inner end portion of said unit is disposed in said dome and the outer end portion is disposed outside the dome and is there formed for the attachment of 65 sander and motive fluid pipes respectively each sander head having sand and fluid ducts respectively that communicate with each other at the inner end, the inner end of each head being formed to provide a downwardly facing inlet 70 mouth for the associated sand duct.

4. In combination with the sand dome of a locomotive having an opening in one side near its bottom, a plurality of sander heads each of a rectangular cross section and having flat engag- 75

ing side faces welded together in horizontal alignment to provide a unit which is engaged and welded in said opening so that the inner end portion of said unit is disposed inside the dome and the outer end portion is disposed outside the dome and is there provided for the attachment of sander and motive fluid pipes respectively each sander head having sand and fluid ducts respectively that communicate with each other at the inner end, the inner end of each head being formed to provide a downwardly facing inlet mouth for the associated sand duct.

5. A sander head for a track sander embodying therein a member having longitudinally extending sand and motive fluid ducts respectively, the said ducts opening through one end of the head and there formed for the attachment of sander and motive fluid pipes respectively, the other end of the sand duct terminating in a downwardly facing inlet mouth and the other end of the motive fluid duct having an angularly disposed part, there being an orifice in the said other end of the head that opens at one end into the angularly disposed part of the motive fluid duct and opens at its other end substantially

10 each other at the inner end, the inner end of each head being formed to provide a downwardly facing inlet mouth for the associated sand duct.

15 5. A sander head for a track sander embodying therein a member having longitudinally extending sand and motive fluid ducts respectively, the said ducts opening through one end of the head and there formed for the attachment of sander and motive fluid pipes respectively, the other end of the sand duct terminating in a downwardly facing inlet mouth and the other end of the motive fluid duct having an angularly disposed part, there being an orifice in the said other end of the head that opens at one end into the angularly disposed part of the motive fluid duct and opens at its other end substantially

20 10 each other at the inner end, the inner end of each head being formed to provide a downwardly facing inlet mouth for the associated sand duct.

25 15 5. A sander head for a track sander embodying therein a member having longitudinally extending sand and motive fluid ducts respectively, the said ducts opening through one end of the head and there formed for the attachment of sander and motive fluid pipes respectively, the other end of the sand duct terminating in a downwardly facing inlet mouth and the other end of the motive fluid duct having an angularly disposed part, there being an orifice in the said other end of the head that opens at one end into the angularly disposed part of the motive fluid duct and opens at its other end substantially

axially into the sand duct above its inlet mouth to provide for the inlet of motive fluid from the motive fluid duct into the sand duct.

6. A sander head for a track sander embodying therein a member having a longitudinally extending sand duct and a laterally spaced, longitudinally extending motive fluid duct, both ducts opening through one end of the said member and there formed to receive sander and motive fluid pipes respectively, the other end of said member 10 being formed to provide a downwardly facing, angularly disposed inlet mouth for the sand duct, said other end of said member being further formed with an angularly disposed portion for the motive fluid duct, there being an orifice in 15 said last mentioned end of said member that opens at one end into said last mentioned portion of the motive fluid duct and opens substantially axially into the associated end of the sand duct and above its inlet mouth to provide for the 20 inlet of motive fluid into the sand duct and a removable plug in the last mentioned end of said member, axially in line with said orifice.
